SUBSCRIBER TERMINAL CENTRAL UNIT

Peter P. Klepa and Thomas J. Hermann, Los Angeles,
Calif., assignors to Hughes Aircraft Company, Culver
City, Calif.

Filed July 6, 1971, Ser. No. 160,266

Term of patent 7 years

Int. Cl. D14—02

U.S. Cl. D26—5 C

Fig. 1.

Fig. 2.

Fig. 4.

Fig. 3.

FIG. 1 is a front, top and right side perspective view of a subscriber terminal central unit showing our new design;

FIG. 2 is a bottom plan view thereof;

FIG. 3 is a left end elevational view thereof; and

FIG. 4 is a rear elevational view thereof.

The perforations, only shown partially on the median band in FIGS. 1 and 3, extended around completely on the top and two opposite sides of the median band.

We claim:

The ornamental design for a subscriber terminal central unit, substantially as shown and described.
